CAN OPENER

George E. Stumpp, Mineola, N. Y., assignor to
Robert N. Rose, Mineola, N. Y.

Application December 2, 1952, Serial No. 323,542

7 Claims. (Cl. 30—10)

1

The present invention relates to can openers and particularly to a device for opening cans by punching an opening in an end thereof as is common for example in the opening of beer cans and oil cans.

More particularly still the present invention relates to a can opener of the type described which is adapted to mounting on a vertical surface such as a wall and which is more convenient in use than is the lever type of opener ordinarily employed for the punching of a hole in the end of a can of beer.

Cans of the type considered are frequently made of relatively heavy gauge metal and are frequently difficult to open with the hand tool supplied. My invention comprises an opener which is operated by means of a cam action so that a large amount of pressure is readily generated and therefore the most difficult can easily opened.

It is an object of the invention to provide an opener for punching holes in an end wall of a container which device is adapted to wall mounting.

It is another object of the invention to provide such a device having an operating mechanism which multiplies the effort expended and makes even the most difficult can readily opened.

It is a further object of the invention to provide such a device as described above which can be economically manufactured.

Other objects and features of the invention will be apparent when the following description is considered in connection with the annexed drawings, in which,

Figure 1 is a side elevation of the can opener of my invention;

Figure 2 is a top plan view of the device of Figure 1;

Figure 3 is a front elevation of the device of Figure 1;

Figure 4 is a fragmentary view similar to Figure 1 but showing parts in an operated position; and

Figure 5 is a fragmentary cross-sectional view showing certain details of the invention, the view being taken on the line 5—5 of Figure 1.

Referring now to the drawings, there is shown at 10 a plate which supports the operating parts of the can opener, the plate 10 being adapted to be fastened to a vertical surface as is indicated by showing of the angle members 9 fixed to the plate and adapted to be fastened to a vertical wall. It will of course be understood that any other suitable means of fastening the plate 10 to a supporting surface may be utilized.

2

Pivottally mounted on the plate 10 is a lever 11, the lever 11 being formed with a hub portion 12 which is rotatably mounted on an enlarged cylindrical portion 13 of a stud 14 screwed into a threaded opening in the plate 10.

Similarly pivottally mounted on the opposite side of plate 10 is a lever 15 this lever being mounted by means of a hub portion 16 on an enlarged cylindrical portion 17 of a stud 18. The lever 15 is provided with a camming surface 20 on one end and with a handle 21 at the opposite end thereof.

Mounted on the lever 11, which is of generally triangular shape, are two rollers 22 and 23 one on each upper corner of the lever 11 as seen in Figure 1. These rollers are mounted on the lever 11 by means of the bolts 24 and 25 respectively which bolts extend through the rollers and the lever and have nuts on the opposite ends thereof.

The rollers 22 and 23 have portions thereof cooperating with the walls of arcuate slots 26 and 27 in plate 10 and further have portions cooperating with the cam surface 20 of the lever 15.

Also mounted on the lever 11 in any suitable manner as for example by welding thereto is a pointed punch or cutter 28 this pointer being rigidly fastened to the lever 11.

Fixed to the plate 10 in any suitable manner as for example by riveting or welding is a vertically extending annular plate 30 the upper edge of which is provided with teeth 31. This member 30 is designed to receive a can to be punched, the upper rim of the can resting on the teeth 31 in the manner clearly shown in Figures 1 and 4.

With the can in the position indicated and with the lever 15 positioned as indicated in Figure 1, the punching operation is initiated. As the handle is moved in the direction indicated by the arrow in Figure 1, the camming surface 20 of lever 15 bears against the rollers 22 and 23 and causes the lever 11 to rotate about its bearing 13. As the lever 11 rotates the point of the blade or punch 28 moves downwardly and penetrates the can forming a triangular opening which extends substantially to the outer cylindrical wall of the can, the movement of the levers 15 and 11 being clearly indicated in Figure 4 which shows the position which the parts will have assumed shortly after the blade has first penetrated the can top.

In order that the device may also be utilized in the opening of bottles provided with crown caps I have formed a bent-over end 32 on the plate 10 this member having portions of opposite curvature 33 and 34 at the top and bottom thereof and a slit intermediate these curved portions

thus forming an opener for bottles capped with crown caps in general accordance with the usual formation of such openers.

While preferred embodiments of the invention have been described it will be understood that various modifications of this invention may be made and therefore I wish to be limited not by the foregoing description but by the claims granted to me.

What is claimed is:

1. An opener for beer cans and the like comprising, in combination, a supporting member, a lever pivotally mounted on said supporting member, said lever carrying a punch and at least one cam follower, and a second lever pivotally mounted on said supporting member, said second lever comprising an operating handle and a cam cooperating with said cam follower to move said first lever thereby causing said punch to penetrate a can held in position beneath said punch.

2. A device as claimed in claim 1 characterized in that said supporting member is a plate and further characterized in that said cam lever is pivotally mounted on one side of said plate and said cam follower lever is pivotally mounted on the opposite side of said plate.

3. A device as claimed in claim 1 characterized in that said first mentioned lever has two cam followers mounted thereon cooperating with said cam of said second mentioned lever.

5. A device as claimed in claim 3 further characterized in that said cam has a contour which produces movement in one direction to cause the punch to penetrate the can and movement in the opposite direction to cause retraction of the

10 punch from the can.

15 6. A device as claimed in claim 3 characterized in that said supporting plate has arcuate slots therein and said cam followers extend through said slots.

7. A device as claimed in claim 3 further characterized in that an arcuate serrated supporting member is fixed to said supporting plate, said serrated member serving to position and support a can the top of which is to be punched.

20 8. A device as claimed in claim 3 characterized in that said cam lever is provided with a handle at a point remote from the pivot whereby a great mechanical advantage is gained.
